UNITED STATES PATENT OFFICE

JOSEPH JACOBS, OF BRIDGEPORT, CONNECTICUT, ASSIGNOR TO THE A. J. DONAHUE CORPORATION, OF MILFORD, CONNECTICUT, A CORPORATION

DESIGN FOR A POWDER PUFF

Application filed October 14, 1931. Serial No. 41,386. Term of patent 14 years.

To all whom it may concern:

Be it known that I, JOSEPH JACOBS, a citizen of the United States, residing at Bridgeport, in the county of New Haven and State of Connecticut, have invented a new, original, and ornamental Design for a Powder Puff, of which the following is a specification, reference being had to the accompanying drawing, forming part thereof.

The figure is a perspective view of a powder puff showing my new design.

I claim:

The ornamental design for a powder puff as shown.

JOSEPH JACOBS.
